UNITED STATES PATENT OFFICE.

GEORGE E. MARLATT, OF PASADENA, CALIFORNIA.

TYPOGRAPHICAL MACHINE.

1,266,970.

Specification of Letters Patent.

Patented May 21, 1918.

Application filed February 2, 1916. Serial No. 76,848.

To all whom it may concern:

Be it known that I, GEORGE E. MARLATT, a citizen of the United States, residing at Pasadena, in the county of Los Angeles and State of California, have invented a new and useful Improvement in Typographical Machines, of which the following is a specification.

My invention relates to typographical machines of the linotype class and the primary object is to provide a simplified and efficient machine embodying a plurality of matrix magazines for receiving, storing and discharging the matrices from which the type slugs are cast.

A further and particular object of this invention consists in the provision of a multiple magazine machine having a single matrix distributing system for returning the matrices to the magazines after use but so arranged as to permit the matrices from two of the magazines to be mixed in the assembled line and automatically distributed to the proper magazine after the casting operation.

A further object is to provide means whereby any one of the several magazines may be moved to a common operative position so that the matrices when they are withdrawn therefrom may fall a fixed and uniform distance to the matrix assembling means.

A further object is to render the individual magazines capable of movement to operative position with a minimum effort on the part of the operator and to render it unnecessary for the operator to leave his seat at the keyboard.

A further object is to provide means for the ready removal of a selected magazine or magazines from the machine and another or other of the magazines substituted therefor, without necessitating the stoppage of the machine or disturbing the operator.

Other objects may appear in the subjoined detailed description of my invention.

Referring to the drawings which accompany and form a part of this specification and in which similar characters of reference indicate the same parts throughout the several views of the drawings, Figure 1 is a right hand elevation of my improved machine showing the magazines and operating means therefor; Fig. 2 is an enlarged for-

ward section of the magazine operating means; Fig. 3 is an enlarged section of the magazine operating screw; Fig. 4 is an enlarged section of the magazine operating lever and cushion means; Fig. 5 is an enlarged section of the magazine operating shaft locking means; Fig. 6 is an enlarged elevation, partly in section, of the magazines and support therefor, the distributing head and the multiple magazine entrances; Fig. 7 is an enlarged section of the lower end of one of the magazines and improved escapement means therefor; Fig. 8 is a rear elevation of a portion of the magazine escapement means; Fig. 9 is a perspective view of the magazine operating shaft and key rods showing the manner of deflecting the key rods to permit the passage of the shaft therethrough; Fig. 10 is a plan of the magazine operating shaft and connections; Fig. 11 is an elevation of the connecting means for the magazine operating means and the distributor entrance channels; Fig. 12 is an enlarged elevation of the exterior of the multiple magazine supports, magazine entrances and distributing means; Fig. 13 is a view showing details of the intermediate channel member; Fig. 13^a is a rear elevation of one of the intermediate entrance channel plates; Fig. 14 is a rear elevation of the machine; Fig. 15 is a plan of the magazines and the adjacent storage rack and removal means; Fig. 15^a is an elevation of the magazine rack showing the magazines suspended thereon; Fig. 16 is a perspective view of a series of entrance partitions; Fig. 17 is a front elevation of the machine showing the multiple magazine system and improved means for raising the assembler elevator to position for the transfer of the assembled line of matrices to casting position; Fig. 18 is an enlarged section of the auxiliary delivery channel supporting shaft and arms. In order to adapt the commonly used types of typographical machines for use with my improved multiple magazine system it is necessary to slightly alter the form of the machine frame 1 in some minor particulars, as for instance, the arm 2 on the right hand side of the machine partakes of a different form from that of the ordinary arm 3 on the opposite side, which arms form supports for the distributing head. The

2
arm 2 is substantially deflected toward the rear of the machine as shown in Fig. 1, and is provided with the rearwardly directed extension 4. An arm 5 on the opposite side 5 of the machine frame and the extension 4 on the arm 2 have alined bearings 6 and 7 which receive the pins 8 and 9 for pivotally holding the opposite multiple magazine frames 10 and 11. The arms 12 and 13 of the magazine frames 10 and 11 are held on the pins 8 and 9 and the lower ends 14 and 15 of the frames are formed with their edges parallel to radial lines from the axis of the pins 8 and 9 and are suitably recessed 10 and cored out as and for the purposes hereinafter described.

The arms 12 and 13 of the frames 10 and 11 are curved forwardly of and clear the distributing mechanism and head regardless of the position of the frames relative thereto and the lower portions 14 and 15 of the frames are arranged for holding several of the matrix magazines 16 in position in the machine and on radial lines from the 25 axis of the pins 8 and 9 in the bearings 6 and 7. The upper ends of the magazines, when in position in the frames, converge and the lower ends are substantially spaced apart in order to provide space for the magazine escapement mechanism and verges.

The magazines 16 are supported on the frames 10 and 11 by means of L shaped bars 17 which extend laterally of and are suitably secured to the top plates 18 of the 35 magazines. The bars 17 overlap and are slidable on the T-shaped bars 19 which parallel the bars 17 and are secured to the bottom plates of the magazines. The ends 20 of the bars 19 are squared to fit into recesses 40 of similar form in the frame portions 14 and 15 and the extensions 21 of the bars 17 on the magazines engage the extensions on the bars 19, as shown in Figs. 1 and 12. A bar 17' is secured to opposite sides of the frame and 45 engages the bar 17 on the upper magazine 16 for supporting the upper magazine while the other magazines are being placed in position on the frame and the lower magazines are suspended one on the other by means 50 of the bars 17 and 19.

Tongues 18' on the upper ends of the magazines are slightly beveled on the sides and engage corresponding recesses in the sides of the magazine frame adjacent to the 65 upper ends of the magazines for independently supporting the converging ends of the magazines. The ends 20 of the bars 19 may be similarly beveled together with their frame recesses, so that when the magazines 60 are placed they will be slightly raised from contact with the magazine below and thus independently supported.

Additional supports for the magazines 16 on the frames 10-11 are provided in the form of the rectangular bars 22 which are

secured to the magazines and are adapted to slidably engage the angle bars 23 which connect the two opposite frame members, this set of bars being provided for each of the magazines and near the lower ends thereof. 70

The left hand, or a selected side of the magazine frame is designed to be closed, as shown in Fig. 12, and the opposite side, as shown in Fig. 1, is designed to be open for the entire length of the magazines in order 75 to permit the insertion and removal of the magazines into and from the frame. It is apparent that in order to insert in and remove a magazine or magazines from the frame it is necessary to provide clearance 80 for the escapement mechanism which is attached to the magazines, and for this purpose clearance openings 24 are provided at the lower end of the right hand frame member 14 so that when a magazine is moved 85 into or out of position in the frame the escapement mechanism will pass through the openings 24 and the magazine will slide, bodily on the bars 17 and 19 and 22 and 23, as hereinafter more fully described. 90

The magazines 16 and the frames 10 and 11 for supporting the magazines are movable as a unit on the fulcrum pins 8 and 9 and the top and bottom plates of the magazines will at all times occupy positions parallel to radial lines from the axes of the pins 8 and 9 and the established space between and the arrangement of the magazines will at all times be preserved when the magazines are moved so as to substitute one for 100 another of the magazines in operative relation to the assembling mechanism.

Means is provided which I will now describe, for maintaining the magazines and frame in a selected position for placing any 105 one of the magazines in operative position relative to the assembling mechanism.

A central rib 25 is provided on the inclined magazine frame floor 26 which has a curved outer edge, so formed as to compensate for the movement of the magazine frame and which is adapted to receive the flanged roller 27 revolvably carried on a pin 28 in the upper end 29 of the magazine operating lever 30. The lower end 31 of the 110 lever 30 is pivoted on a stud 32 at the base of the machine frame column to the frame 1, and at a point slightly below the center of the lever a boss 33 is formed on the lever with an internal slot or recess 34 for pivotally receiving the end 35 of a link 36 which is pivoted to the lever on a pin 37 and the opposite end or stem of the link is slidably 120 in the end 38 of a tube 39 which is slidably mounted in a lug 40 formed on the rear edge 115 of the frame 1.

The stem of the link 36 carries a spring 41 which is compressible between the end 38 of the tube 39 and the side of the boss 33 of the lever 30 when the lever is moved in 130

the direction of the tube. The tube 39 carries a relatively stronger spring 42 which is compressible between the flange 43 on the inner end of the tube and the inner side of the lug 40 on the frame 1. By means of this arrangement, the initial movement of the lever 30, when the magazine frame is lowered for the purpose of changing the magazines, compresses the inner spring 41 until the side 10 of the boss 33 on the lever 30 engages the flange 43 on the tube 39, when the tube will be caused to slide in the lug 40 on the frame and thus compress the relatively strong spring 42. The increasing tension of the 15 springs 41 and 42, as the lever 30 moves outwardly, serves to overcome the force of gravity when the magazines and frames approach their lowest positions in the machine, for it is apparent that when the magazine 20 frames are at their highest point the roller 27 will rest approximately above the fulcrum stud 32 of the lever 30 and less tension is required to overcome gravity than when the frames are at their lowest point.

25 The movement of the magazines and their supporting frames is accomplished by means of a transverse operating shaft 44 which is journaled in bearings 45 and 46, at the rear and front, respectively, of the machine frame 1. The central portion of the shaft 44 has a screw 47 which is sufficiently elongated and extends through a bore 48 in the lever 30 above the boss 33 and on which a nut 49 is threaded. Links 50 which are 30 pivoted to the lever 30 and the nut 49 on opposite sides by means of screws or pins 51 and 52, operably connect the nut and lever, so that when the shaft 44 is turned the screw 47 will move longitudinally of the 35 shaft and cause the lever 30 to move therewith.

40 The forward end of the shaft 44 extends conveniently outward from the boss 33 on the bearing 46 and the shaft is provided near its rear end and on the inner side of the bearing 45 with a set collar 55 which prevents a rearward movement of the shaft. An operating crank 56 having a suitable handle 57 is diametrically pivoted to the 45 front end of the shaft 44 on a pin 58 and is provided with an annular flange 59 which encompasses the boss 33 of the bearing 46. A radial rib 60 is formed on the inner side of the crank 56 which is adapted to engage 50 and seat in a radial slot 61 formed in the outer end of the boss 33 for the purpose of locking the crank to the shaft.

55 The magazine operating mechanism just described serves to move the magazines and frame on their axes so as to place a selected magazine in operative relation with the assembling mechanism, and when the rib 60 on the crank 56 is seated in the slot 61 in the boss 33 the shaft 44 will be prevented 60 from rotation in its bearings. The disen-

gagement of the rib 60 from the slot 61 by moving the handle 57 outwardly from the frame permits the crank 56 to be turned and the screw 47 on the shaft 44 will move the nut 49 forwardly or backwardly on the shaft 44 according to the direction the crank is turned, and, as hereinbefore stated, the movement of the nut also causes the movement of the lever 30 for a corresponding distance, the movement of the lever permitting and causing the movement of the magazines at their lower ends either upwardly or downwardly, as the case may be. 70 A pinion 62 on the shaft 44 adjacent to the inner side of the bearing 46 at the front end of the shaft meshes with and operates 75 a gear 63 which is pivoted to the frame 1 on a pin 64 and an index or pointer 65 is attached to the outer end of the pin 64 for the purpose of indicating to the operator 80 the movement of the magazines. Suitable 85 graduations are provided on the frame adjacent to the pointer 65 and as the shaft 44 is turned for moving the magazines into and out of operative position, the pointer is 90 turned by means of its geared connection with the shaft, so that the position of the magazines may be accurately determined and established from the front of the machine without the necessity of the operator 95 leaving his seat at the keyboard.

The outer end of the pin 9 which forms the axis for one side of the magazine frame is extended inwardly from the bearing 7 in which it is pivoted and is slotted to receive 100 the upper end of a bar 66 and is secured to this bar by means of a pin 67. The lower end of the bar 66 engages the upper arm 68 of a bell crank 69 which is pivoted on a screw 70 to an arm 71 depending from and secured to the pin 9 at the upper end. A 105 stud 72 carried by the lower end of the bar 66 extends through a suitable opening in the bell crank arm 68 and is provided on the opposite side of the bar 66 with a spring 110 73 which is held in tension between the arm 68 and a washer 74, a nut 75 being provided on the end of the stud and the bar 66 and the arm 68 being thus held in resilient engagement.

The lower arm 76 of the bell crank 69 is pivoted at 77 to the upper end of a bar 78; the lower end of the bar 78 is pivoted to the outer end of an arm 79 fixed to a longitudinal shaft 80 which is journaled in bearings 81 and 82 on the rear of the arms 2 and 3; an arm 83 fixed to the shaft 80 and similar to the arm 79 which is positioned near the center of the machine in the plane of the lever 30, is pivoted to the upper end of a 120 bar 84; and the lower end of the bar 84 is pivoted to a vertically slidably lock 85 on a pin 88.

The lock 85 has a vertical slot 86 through which the rear end of the shaft 44 extends 125

and is held on the shaft by means of a set collar 87. The lock 85 has horizontal lugs 89 formed thereon at the top and bottom which are extended inwardly and parallel with the shaft 44 and are adapted to engage and seat between the teeth 90 of a gear 91 which is fixed to the shaft 44 at the rear of the bearing 45 and prevents a forward movement of the shaft in its bearings. The space between the locking lugs 89 on the lock 85 is slightly greater than the outer diameter of the gear teeth so that the lock may be so positioned as to provide clearance between the gear and both of the locking lugs.

The arms 71 and 71' on opposite sides of the machine serve as supports for the multiple distributor entrance which is composed of the frame members 92 and 93 and the channel members 94 and 95. The arm 71 is held normally in the position indicated in Fig. 6 by means of the engagement of the bell crank arm 68 with the fixed arm 66 and the tension of the spring 73. In the event of a matrix becoming bent and failing to entirely enter the channels of the matrix magazines, which frequently occurs in the operation of typographical machines, the matrix 96 would lock the intermediate channel member 94 and the magazine 16 so as to prevent the movement of the magazine, or otherwise damage would result to some of the machine parts in the event an attempt were made to move the magazine before the obstructing matrix were removed.

An attempt to move the magazine in such case, with the use of my improved mechanism, would result in a slight movement of the intermediate channel member 94, and this movement would effect a slight movement of the arm 71 and the bell-crank 69 in a direction corresponding to the direction of movement of the magazine. The movement of the bell crank rocks the shaft 80 on the back of the machine in its bearings and by means of the hereinbefore described connections with the lock 85, one or the other of the locking lugs 89 will engage the ratchet or gear 91 and prevent the further rotation of the operating crank 56 until the obstructing matrix has been removed.

In order to accommodate the key rods 97 to the movement of the magazines when they are changed from one to another position relative thereto, the upper ends of the rods 97 are deflected sufficiently to properly engage the escapement verges 98 at the lower ends of the magazines to conform to my improved arrangement of the magazines. Vertical levers 99 are pivoted at their lower ends to a longitudinal shaft 100 which extends across the machine frame and is journaled at opposite ends in brackets 100'. The upper ends of the levers 99 are pivoted 65 to the horizontal key rod guide plate 101

which has rectangular perforations 102 through which the key rods 97 are extended and through which they move freely when actuated by the key bars on the keyboard, in the ordinary manner.

Brackets 103 are formed on, or they may be suitably secured to the front frame member for holding and slidably receiving the forward portion of the guide plate 101 so that when the key rods are moved forward or backward, the guide plate will move on the brackets a corresponding distance and will at all times retain its normally horizontal position. The levers 99 are connected midway of their extremities by means of a rod 104 and the rear end of an arm 105 is pivoted to the rod 104 about midway between the levers 99, the arm 105 having a notch 105' in its forward end 104' which is adapted to engage the edge of the flange 59 on the operating crank 56. This connection between the levers 99 and the crank 56 serves to operably connect the bank of key rods 97 with the operating crank 56 so that when a change of magazines is made the outward movement of the crank 56 will effect the simultaneous and uniform movement of all of the key rods 97 outwardly from the magazines and permit the passage of the lower ends of the magazines 16 by 95 the upper ends of the key rods. The arm 105 is prevented from longitudinal movement on the rod 104 by means of pins 105' secured in the rod 104 on opposite sides of the arm, as shown in Fig. 10.

It is necessary, in order that the escapement verges may be actuated at their forward ends by the key rods 97 to permit the engagement and disengagement of the key rods therewith, to provide a duplex series 105 of verges, each verge of the series being separately pivoted on rods 98^a and 98^b. The lower series of verges 98 are mounted on the rod 98^a and the upper series 98' on the rod 98^b. The two series of verges are adapted to act in unison for releasing the matrices 96 from the magazines 16 in the usual manner and the co-acting verges 98 and 98' of each series are resiliently connected by means of springs 98^c which restore the 115 verges to normal position after a matrix has been released. The springs 98^c are coiled about the wire from which they are formed, the straight portion of the wires extending through slots 98^d in the rear ends 120 of the forward verges and terminating in loops around the end forward ends 98^e of the rear verges. The inner ends of both sets of verges have pawls 98^f which extend through slots in the bottom magazine plates 125 and operate to release the matrices in the magazines in the usual manner.

The operation of the forward verges 98 for releasing the matrices from the magazines also effects the operation of the rear 130

verges 98' by means of the connections through the springs 98^c, the verges 98' serving to prevent the passage of the second matrix in the channel from the lower end. 6 The springs 98^c restore the verges to normal position after their operation for releasing the matrices and re-align them with their pivot rods 98^a and 98^b.

In the event of an overstroke of a key 10 rod 97, or in the event that a matrix is in such position as to prevent the operation of the rear verges 98', which sometimes occurs, the forward verges will operate as usual and compress the springs 98^c without operating the rear verges 98'.

It will become more fully apparent as the description of my invention progresses that it is necessary to stop the operation of the distributor screws 106^a, 106^b and 106^m 20 when the magazines are being moved from one position to another, and in order to accomplish this result I provide the ordinary distributor driving pulley 106, which, instead of being fixed to the intermediate 25 driving shaft 107 of the machine, is loosely mounted on the shaft and is normally driven by frictional engagement with the outer flange 108 of a clutch member 109 which is fixed to the shaft 107 and is slideable on the 30 shaft. A spring 110 is carried by the shaft 107 and is compressible between the flange 111 of the clutch and a set collar 112 on the shaft, thus holding the clutch in resilient and frictional engagement with the pulley 35 106 for effecting the operation of the distributor screws. A set collar 113 is fixed to the shaft 107 on the opposite side of the pulley 106 from the clutch 109 for receiving the thrust of the pulley and also for frictionally 40 engaging the opposite side of the pulley.

The pulley 106 is operably connected with the distributing mechanism by means of the intermediate pulleys 106^a and 106^b carried by a shaft 106^c which is journaled in 45 a bracket 106^d at the rear of the machine, the belt 106^e connecting the pulleys 106^a and 106^a, the belt 106^f connecting the pulleys 106^b and 106^b on the shafts 106 and 106', respectively, the shaft 106' being common to all 50 machines of this class, and gears 106^h and 106ⁱ which drive the distributor screws 106^k, 106^l and 106^m.

The arrangement of the distributor driving belts is different from the ordinary arrangement, and necessarily, for the purpose of preventing the interference of the belts with the movement of the magazines 16 when they are withdrawn from the magazine frame 14. The magazines 16 are removable from and insertable laterally in the frame 14 through the opening in the frame, from which position, after their removal, they may be lowered on a rack positioned adjacent to the side of the magazine frame 65 and which has parallel bars 24^a, to a position

from which they may be removed to a place of storage.

The bars 24^a are integral with or may be suitably secured to stems 24^b which are slidably disposed in and extend entirely through a swivel block 24^c. The stems 24^b are arranged in diagonal planes at right angles, or substantially so, relative to each other, and are positioned on opposite sides of the center of the block 24^c. The stems are held in a desired position in the block by means of transversely disposed pins 24^d which engage annular grooves 24^e in the stems 24^b of the bars. The block 24^c has a stem 24^f which is pivotally supported in the bracket 24^g formed on and extending outwardly from the arm 2.

As a magazine 16 is withdrawn from the frame 14 the T bar 19 on the magazine which is to be removed slidably engages the bar 24^a on the swivel rack, and when completely withdrawn from the frame, the magazine may be suspended vertically from the rack as indicated in broken lines in Fig. 15, one of the flanges of the T in such case resting in the recess 24^f of the bar 24^a (Fig. 15^a). The magazine may be then removed to a convenient place of storage, or, it may be pivotally moved with the swivel block 24^c to the rear position shown in Fig. 15, and so held for further use. The movement of the block 24^c for disposing of the removed magazine places the other bar on the block in the position previously occupied by the first bar to permit the insertion of a new magazine.

Either of two methods may be utilized for alining the bars 19 on the magazines with the bars 24^a on the rack. The rods 24^b which carry the bars 24^a may be adjusted relative to the swivel block 24^c by means of the retaining pins 24^d which engage the annular grooves 24^e in the rods or stems 24^b, the pins being removed from the block 24^c and re-inserted so as to engage a different one of the grooves 24^e in the stem to be adjusted; or, the magazine 16 may be raised or lowered to correspond to the position of the bars 24^a, for removal, by the operation of the handle 57 on the crank 56, as described.

It should be understood that the magazines may be inserted in and removed from the frame 14 during and without stopping the operation of the distributing mechanism, and that any magazine other than that in operative position may be removed by an attendant without disturbing the operation of the keyboard by the adjustment of the stems 24^b so as to register with the T bar 19 of a magazine selected to be removed. A magazine which may have been temporarily removed and turned to the rear position shown in broken lines in Fig. 15, may be restored to the proper position for insertion in the frame 14 by moving the swivel block 24^c 130

on its axis until the rack bar 24^a is properly aligned with the T-bar 19, the magazine being then inserted in the position in the frame from which it was removed, or, in 5 another position; provided that the frame 14 is moved by operating the crank 56 by means of the handle 57.

From the description of the magazine rack, it is readily apparent that any magazine 10 may be readily transposed so as to register with the auxiliary delivery channel 124, as shown in Fig. 6 and which will be hereinafter described, and may be rendered capable of cooperation with the magazine in 15 regular operative position in the machine. The rack bars 24^a, when not in use, may be tilted with their stems 24^b to the positions shown in broken lines in Fig. 1. The rear bar carried by the stem 24^b closest to the 20 supporting arm 2 is first tilted, and the front bar carried by the outer stem, is then tilted and serves to retain the inner bar in its tilted position. The bars 24^a, as shown in full lines in Fig. 1, occupy horizontal planes, 25 and when they are tilted as described, by the turning of their stems 24^b in the block 24^c, the bars occupy inclined positions, as represented by the broken lines. The outer bar is then manually engaged by a latch 24^d 30 suitably pivoted on the arm 2, the latch thus holding both bars in their tilted positions for the purpose of economizing space at the side of the machine. The fulcrum pin of the latch 24^d should be of sufficient length 35 as to position the latch in a plane coincident with the vertical center of the block 24^c, or nearly so.

When the key rods 97 are moved forward, as hereinbefore described, to permit the 40 movement of the magazines, a latch 114 which is fixed to the crank shaft 136 and is in normal engagement with an arm 115 of a clutch actuating lever 116 effects the operation of a clutch lever which is pivoted at 45 117 to a lug 118 on the machine frame 1 and the arm 119 of the lever 116 moves the clutch 109 out of contact with the pulley 106 on the shaft 107 by means of the engagement of the clutch lever arm 119 with the 50 annular groove 120 formed between the flanges 108 and 111 of the clutch, thus preventing the operation of the distributor screws. The shaft 107 is driven by means of a belt 121 from the main driving shaft 55 of the machine which runs over and operates a pulley 122 on the shaft 107.

It is preferable to locate the magazine operating means of my invention approximately above the center of the keyboard in 60 proximity to the operator, and this necessitates the extension of the magazine operating shaft 44 through the bank of key rods 97 and the deflection of at least two of the key rods, as shown in Fig. 9, to provide

clearance for the shaft. The rods 97 are 65 preferably cut on opposite sides of the shaft 44 and are deflected outwardly from the shaft for a distance sufficient to permit the shaft 44 to clear the rods. The upper and lower portions of the rods thus cut are 70 rigidly connected by means of angle plates 123 which are suitably secured to the rod sections by rivets or screws and a central opening is formed in and between the plates of sufficient area to permit the free move- 75 ment of the shaft and rods.

In order that the matrices from two magazines may be mixed in a line, I provide an auxiliary matrix delivery channel 124 which is connected with the main delivery channel 80 125, as shown in Fig. 6. When the auxiliary channel 124 is lowered to operative position, as shown in full lines, it is unnecessary to stop the operation of the distributing mechanism and means is provided in 8. this invention to this end. The auxiliary channel 124 is suspended from a rock-shaft 126 which is journaled in arms 127 and 128 on opposite sides of the machine frame and the member 124 is held by arms 129 secured 90 to the channel plate 130. The channel member 124 may be moved laterally to any one of several positions according to the character of the matrices to be withdrawn from the upper magazine; for example, when figures or small capital letters are to be drawn from the upper magazine, the member 124 may be placed in a central position relative to the keyboard; if an occasional group of capital letters were desired the member 124 95 may be moved to the extreme right; and if an occasional "lower case" group were desired from the upper magazine this member may be moved to the extreme left. Because of the fact that the member 124 connects 105 with comparatively few of the key rods in any one of its several positions, the matrices may ordinarily be withdrawn from two magazines while certain groups of keys are for the time being reserved for use only in 110 connection with the upper magazine. For instance when small capital letters or figures are to be taken from the upper magazine and mixed in a line with matrices from the lower magazine, it is unlikely that small 115 capitals or figures of a different kind would be used in the same line. Thus the groups of keys controlling such characters could be temporarily reserved for use in connection with the upper magazine. This arrangement causes the matrices thus mixed from two magazines to be returned to their proper magazines, as will be hereinafter described. The shaft 126 has a longitudinal groove 132 of sufficient length to permit the 12 maximum lateral movement of the channel member 124 and pins 131 are secured in the upper ends of the arms 129 which engage

delivery means when lowered to operative position oscillates the movable section 146 of the distributor entrance channel and causes this movable section to register with 5 the magazine next above the one in normal and regular operative position.

The auxiliary delivery means is movable longitudinally on the shaft 126 to a position opposite a selected movable section 146 of 10 the distributor entrance and the connecting rod 154 may be readily disconnected from one set of the hooks 154' and connected with another set of the hooks on another of the sections of the distributor entrance. The 15 rod 154 may also be disconnected at one or both ends when it is desired to use but a single magazine so as not to interfere with the opening and closing or the movement of the distributor entrance as a unit for purposes which will appear later on in the description.

The intermediate channel entrance 94 which operates the connecting rods 78 and 84, as hereinbefore described, in addition, 25 cooperates with the usual channel entrance 95 for guiding the matrices from the distributor bar 155 to any of the magazines 16, regardless of their position in the machine. For use in a four magazine machine this 30 channel entrance is made with seven channels as shown in Fig. 6, so that with any of the magazines in operative position each of the other magazines will register with one of the other intermediate channels for 35 purposes which I will now describe.

The magazines of typographical machines as heretofore constructed are incapable of movement relative to the channel entrance until all of the matrices in a previously set line have been distributed, as otherwise the matrices would be distributed to the wrong magazine; whereas in my improved means it is unnecessary for an operator to wait for the distribution of a previously set line before changing the position of the magazines.

The usual channel entrance 95 is mounted on a frame 93 which is pivotally held on arms 156 attached by means of pins or 50 screws 157 to the arms 71 and 71' to which the intermediate channel entrance 94 is also secured by common means. The upper ends of the arms 156 terminate with the intermediate channel entrance partitions 95 immediately beneath the matrices 96 as they depend from the distributor bar 155. The trunnions 159 support the frame 93 in the ends of the arms 156 and form the axis of a circle to which the upper edges of the intermediate channel plates 160 conform in 60 position, so that the channel entrance 95 may be radially moved about the axes of the trunnions for registering the lower end thereof with a selected one of the interme-

diate channels for conducting the matrices 65 to a selected magazine, whether in operative or inoperative position.

The channel entrance 95 is held normally in position for delivering the matrices to the magazine which is in operative position 70 in the machine by means of a spring 161 which is secured at the upper end to the end of the frame 93 of the channel entrance as shown in broken lines in Fig. 12, and at the lower end to the arm 156. The channel entrance 95 is movable pivotally about its axis against the tension of the spring 161 and with the movement of the operative magazine for a sufficient period of time to permit the delivery of any undistributed matrices 75 to the magazine which is being moved from operative position, the distributor screws being stopped as hereinbefore described, while the magazines are being moved.

In order that the channel entrance 95 may 85 be thus moved with the magazine 16, I provide an arm 162 (Fig. 12) which is pivoted to the frame member 11 on a pin 163 and the opposite end of which has a plurality of notches 164 which correspond in number to the number of the magazines 16 accommodated by the magazine frame 10-11. A pin 165 which is secured in the end of the channel entrance frame 93 is adapted to engage one of the notches 164 which corresponds to the particular magazine in operative position. The arm 162 serves to operably connect the frame 11 with the channel entrance 95 so that a corresponding and simultaneous movement of the magazine and 100 channel entrance may be effected for the purpose described. A spring 166 which is attached at opposite ends to the arm 162 and the lower portion of the frame 11 maintains the normal engagement of the arm with the 105 pin 165.

After the magazine frame has been raised or lowered to bring a selected magazine to operative position, the matrices may be immediately drawn from the magazine so selected; but, before such matrices are carried to the distributor entrance channel must be restored to normal position, sufficient time having elapsed to permit the distribution of the previously used matrices. This 110 restoration of the entrance channel is accomplished by means of a lever 167 which is pivoted to the frame 11 on a pin 168, the upper end of the lever terminating beneath and engaging the edge of the arm 162 and 115 the lower end of the lever depending from the frame to a position convenient to the operator.

The movement of the lower end of the lever 167 raises the upper end thereof and 120 releases the arm 162 from the pin 165, thus permitting the entrance 95 to move into normal position by means of the tension of

the groove 132 so that a movement of the member 124 will effect a movement of the shaft 126 when the channel member 124 is moved to an inoperative position, as indicated in broken lines in Fig. 6.

One end of the shaft 126 carries a short lever 133 which is fixed to the shaft and pivoted at the end to the vertical connecting rod 134. An elongated slot 135 is formed in the lower end of the rod 134, as shown in Fig. 11, which receives the crank end 136 of the shaft 104 for the purpose of connecting and effecting the simultaneous operation of the shafts 104 and 126 and the disengagement of the latch 114 from the clutch arm 115, so that the bank of key rods 97 may be moved out of operative relation with the escapement mechanism without stopping the operation of the distributing screws. The handle 57 on the crank 56 may be moved outwardly, for disengaging the rib 60 on the crank from the slot 61 in the boss 53 without turning in order to disconnect the upper ends of the key rods 97 from one of the magazines and connect them with a series of intermediate key rods 137 carried by the auxiliary delivery channel 124.

When the latch 114 is engaged with the bell crank 115, the spring 110 serves to retain the engagement of the key rods 97 with the verges 98, provided that the rib 60 on the crank 56 is in registration with the slot 61 in the boss 53; but when the latch 114 is disengaged from the bell crank 115, the spring 110 does not so act and the key rods 97 will engage the dogs 138. Also the crank 56 may be moved slightly without materially changing the positions of the magazines, so that the rib 60 cannot reenter the slot 61 while the auxiliary delivery means 124 is operative. When in such position and while the crank 56 is being turned, the rib 60 and a similar rib 60^a movably engage the full face of the boss 53, and thus prevent any shifting of the key rods during the rotation of the crank.

The forward movement of the key rods 97 moves the upper ends thereof from beneath the verges 98 to positions beneath the free ends of a series of dogs 138 which normally form a part of the rear wall 139 of the main delivery channel 125. The series of dogs 138 are commonly mounted on a longitudinally disposed rod 140 which is supported at convenient intervals on brackets 141 formed on the rear wall 139 of the channel 125. When the key rods 97 and the dogs 138 are in operative relation and the key rods are operated in the usual manner, the dogs are actuated by the key rods 97 and engage and actuate the auxiliary series of key rods 137 which are pivotally mounted on a rod 142 carried by arms 143 formed on the rear wall 144 of the auxiliary delivery channel 124.

The auxiliary key rods 137, when actuated as above described, engage and actuate the verge pawls 98 of the magazine 16 next above the magazine which is in regular operative position in the machine and with which the auxiliary delivery channel 124 is connected, 65 as shown in Fig. 6. The downward movement of the auxiliary key rods 137 is limited by means of a rod 145 carried by the arms 143, when the auxiliary delivery channel 124 is being moved out of operative 70 position, or, in approaching operative position, when swung downwardly.

This arrangement of main and auxiliary key rods and associated mechanism permits the withdrawal of the matrices from either 80 of the two magazines thus connected with the delivery mechanism, the movement of the bank of key rods 97 backward or forward serving to operably connect the key rods with either of the magazines from 85 which it is desired to extract the matrices.

The mixture of the matrices from the two magazines in an assembled line necessitates the provision of means for returning the matrices to the particular magazine from 90 which they were withdrawn and for this purpose the distributor entrance channels are subdivided into a plurality of movable sections, as shown in Fig. 16. The movable sections of this entrance correspond to that 95 part of the keyboard which designates the characters most likely to be contained in a magazine other than the one in operative position, as for instance, figures and small capital letters, which are ordinarily placed 100 at the central position and to the extreme right of the key-board.

In the fragmentary view of the distributor entrance shown in Fig. 16 the movable section 146 and the relatively stationary sections 148 are held on a frame 93 by means of screws 149. The movable section is mounted between the stationary sections and the end partitions 150 of the movable section are held in contact with the end partitions 151 of the stationary sections and hingedly secured thereto by means of rivets 152 at their upper ends. Two of the entrance partitions near the center of the movable section 146 have hooks 154 which are 115 adapted to engage, in the event that two magazines are to be used co-operatively, a pin 153 which is carried by a connecting rod 154 connected with and movable longitudinally by the operation of the auxiliary 120 delivery channel 124 when the latter is moved to or from operative position.

The connecting rod 154 is operably connected with the channel member 124 by means of the forward bifurcated end 155 125 which is engaged by a rod 156 held in the arms 129 of the channel member plate 130; by means of which connection the auxiliary

the spring 161. The restoration of the entrance to normal position, after another magazine has been moved into operative position, permits the engagement of the notch 5 in the arm 162 which corresponds to the new magazine with the pin 165.

The channel plates 160 which form the intermediate channels in the member 94 are held in spaced relation by means of the end 10 plates 169 and at convenient intervals between the ends by means of the partitions 158. The partitions are preferably made in two parts for convenience in assembling, the exterior edges overlapping and being held 15 together by means of a rod 170, which is preferably continuous for connecting and upon which the partitions 158 are threaded. Each of the channel plates 160 is slotted on the opposite edges, as at 171, to receive the edges of the partitions and prevent their displacement.

The channel entrance 95 and intermediate channel entrance 94 are held in normal position by means of springs 172 which are 25 attached at their lower ends to arms 173 fixed to the pins 157 to which the channel entrance is also fixed, and at their upper ends to the pins 70 in the arms 71 and 71'. The intermediate channel frame 92 has 30 lugs 174 on the upper end and on opposite sides which hold adjusting screws 175 and pins 176 are secured in the arms 71 and 71' which are adapted to coact with the adjusting screws for limiting the forward movement 35 of the frame 92. Lock nuts 177 are provided on the adjusting screws 175 in order that the adjusting screws may be permanently adjusted to a desired position.

The primary and intermediate channel entrance by means of their common supports may, in the event of an obstruction in the channel entrance, or, for the purpose of affording access to the magazines, be moved outwardly and backwardly from their normal position, as indicated in broken lines in Fig. 6, against the tension of the springs 172. This movement of the entrances is limited 45 downwardly by means of pins 178 which are carried by the lower extended ends of the arms 71 and 71' and with which the arms 50 173 on the pins 157 engage.

In Figs. 6 and 14 I show a channel bar 179 which overhangs the channel entrance plate 180 and is adapted to move slightly thereby 55 with for accurately guiding the matrices into the channel entrances when they drop from the distributor bar 155. The bar 179 has arms 181 at opposite ends by means of which the bar is suspended from brackets 60 182 secured to the distributor head 183 on pins 184. Ribs 185 are formed on the bar 179 and correspond in number and position to the partitions in the channel entrance, thus serving to guide the matrices by their

upper ears into the entrance channels immediately after they drop from the distributor bar 155.

Having thus described my invention, what I claim is:

1. A typographical machine having a plurality of matrix magazines, common supporting frames therefor at opposite sides of the machine, openings being formed in one of said supporting frames to permit the insertion and removal of said magazines, means insertible in said frames and attached to said magazines for rendering the magazines slidable relative to the frames, and means for raising and lowering said magazines for selective use, including a yieldable element in engagement with and for supporting said magazines.

2. A typographical machine having a plurality of matrix magazines, a pair of supporting frames for slidably receiving and holding said magazines in position for use, means being provided on said magazines and insertible in said frames for removably holding said magazines in position in the frames, means for raising and lowering said frames, including counterbalancing means for the weight of the magazines during action, and means for rendering said magazines selectively operative.

3. A typographical machine having a plurality of matrix magazines commonly supported in planes converging at their axis, said axis being substantially spaced from the receiving ends of said magazines, matrix distributing means common to all of said magazines, magazine entrance means intermediate of said distributing means and said magazines, matrix delivery means arranged for connection with two of the said magazines, means for raising and lowering said magazines for selective connection with said entrance and delivery means, said magazines having matrix escapement means thereon and key rods being provided in the machine for operating said escapement means, and means connected with said magazine operating means for disconnecting said escapement means and said key rods when the magazines are moved.

4. A typographical machine having a plurality of matrix magazines commonly supported therein, matrix distributing means common to all of said magazines, magazine entrance means comprising relatively adjustable channel elements intermediate of said magazines and said distributing means, commonly movable to and from operative position, matrix delivery means arranged for connection with two of said magazines, means for connecting said delivery means and said magazine entrance means for simultaneous adjustment, and means for adjusting said magazines relative to said de-

livery and entrance means for rendering two of said magazines simultaneously operative.

5. A typographical machine having a plurality of matrix magazines commonly supported therein, matrix distributing means common to all of said magazines, and means intermediate of said distributing means and said magazines for delivering the matrices, after use to two of said magazines, said 10 means comprising commonly supported channel elements arranged for selective association with each other and with said magazine, said magazines being adjustable relative to said means, and said means being movable to and from operative position at will.

15. 6. A typographical magazine machine having a plurality of matrix magazines commonly supported therein, matrix distributing means common to all of said magazines, 20 and magazine entrance means comprising commonly supported primary and auxiliary elements movable into and from operative position, said primary element having a plurality of channels arranged for selective connection with the channels in the magazines, said magazines being movable relative to said primary element for establishing such connections, and said auxiliary element having channels arranged for selective registration with the channels in said primary element, for returning the matrices from said 25 distributing means to the proper magazine.

7. A typographical machine having a plurality of matrix magazines commonly supported therein, matrix distributing means common to all of said magazines, and magazine entrance means including a multiple channeled primary element arranged for selective connection with said 30 magazines and an auxiliary element connected with said distributing means and capable of selective connection with the channels of said primary element, said primary and auxiliary entrance elements being commonly movable to and from operative position relative to said magazines and said distributing means.

8. A typographical machine having a plurality of magazines for storing the matrices commonly supported therein, matrix distributing means common to all of said magazines, and magazine entrance means intermediate of said magazines and said distributing means including primary and auxiliary elements arranged for selective connection with said magazines for delivering the matrices from said distributing means to the proper magazines, said primary and auxiliary entrance elements being commonly supported and movable from operative connection with said magazines and said distributing means.

9. A multiple magazine typographical machine having means for rendering two of

said magazines simultaneously operative, including in combination with the primary delivery means connected with one of said magazines, a single matrix-distributing system capable of connection with all of said magazines, of a channel entrance member 70 movable into and from operative relation with said magazines, an intermediate channel member connecting said distributing means with said channel entrance means and movable relative thereto, and auxiliary delivery means connected with another of said magazines and with said intermediate channel member, said delivery and entrance means being capable of operation respectively for selectively releasing the matrices 80 from and distributing the same to the proper magazines.

10. A typographical machine having a plurality of matrix magazines rigidly supported in converging planes in the machine, 85 a distributing system therefor, a primary magazine entrance element pivotally supported in the machine and having a plurality of banks of channels formed therein capable of registration with the channels in 90 the magazines, an auxiliary entrance element pivotally supported below said distributing means and having channels communicating with the channels in said primary element, said primary and auxiliary elements being 95 movable from operative position relative to said magazine, said auxiliary element being movable for registering the channels therein with selected channels in said primary element, primary matrix delivery means connected with one of said magazines, and auxiliary delivery means connected with an adjacent magazine and with said auxiliary entrance means for simultaneously rendering two of said magazines operative.

11. A typographical machine having a plurality of matrix magazines, primary and auxiliary delivery means connected therewith, matrix distributing means also connected therewith, and primary and auxiliary 110 magazine entrance means composed of relatively movable elements having channels capable of being brought into selective registration for distributing the matrices to their proper magazines, said auxiliary entrance and delivery means being connected for simultaneous movement.

12. A typographical machine having a plurality of matrix magazines, primary and auxiliary matrix delivery means connected 120 with two of said magazines, said auxiliary delivery means being movable from operative relation with the magazines, a single matrix distributing system therefor, a plural channeled primary magazine entrance element 125 capable of selective registration with said magazines, auxiliary entrance means intermediate of said distributing means and said

primary entrance means, operably connected with said auxiliary delivery means for simultaneous operation therewith, and means for moving the magazines into selective positions relative to said entrance and delivery means.

13. A typographical machine having a plurality of matrix magazines, a single matrix distributing system common to all of said magazines, a primary magazine entrance means including a plurality of banks of channels arranged for selective registration with the channels in said magazines, auxiliary entrance means movable pivotally relative to said primary means for registering the channels therein with the channels in said primary means, primary matrix delivery means connected with one of said magazines for receiving the matrices therefrom and auxiliary delivery means communicating with said primary delivery means and with another of said magazines, and means for connecting said auxiliary delivery and said auxiliary entrance means for simultaneous operation.

14. A typographical machine having a plurality of matrix magazines, primary and auxiliary matrix delivery means arranged for independent connection with two of the magazines, matrix distributing means for returning the matrices to the magazines after use, and primary and auxiliary entrance means arranged for independent connection with the two operative magazines and for connection with each other, for effecting the simultaneous movement thereof into and out of operative position; said auxiliary entrance and delivery means being simultaneously operable.

15. A typographical machine having a plurality of matrix magazines, and primary and auxiliary matrix delivery and magazine entrance means arranged for operative connection with two of said magazines, said primary entrance and delivery means being connected with one of the magazines and said auxiliary entrance and delivery means being connected with another of the magazines and arranged to move in unison for rendering the same operative and inoperative, selectively, relative to their respective magazines.

16. A typographical machine having a plurality of matrix magazines, primary and auxiliary matrix delivery means and magazine entrance means arranged for connection with opposite ends of two of the magazines, the primary delivery means being stationary relative to and together with the primary entrance means connected with one of the magazines, and the auxiliary delivery and entrance means being movable respectively relative to and connected with the other of said operative magazines and said primary

entrance means and arranged for simultaneous operation.

17. A typographical machine having a plurality of matrix magazines, primary and auxiliary matrix delivery means arranged for connection with the discharging ends of two of said magazines and connected together for guiding the matrices when discharged therefrom and primary and auxiliary entrance means arranged for connection with the receiving ends of said operative magazines and connected together for commonly receiving and delivering the matrices to their respective magazines, said auxiliary entrance means being movable relative to the magazines and adjustable relative to said primary entrance means.

18. A typographical machine having a plurality of matrix magazines operably connected at the discharging and receiving ends, respectively, with primary and auxiliary matrix delivery means and primary and auxiliary magazine entrance means, said primary and auxiliary delivery means being connected for guiding the matrices in their discharge from the magazine, and said primary and auxiliary entrance means being adjustable relative to each other and connected for receiving the matrices and effecting their delivery to selected magazines after the casting operation.

19. A typographical machine having in combination, primary and auxiliary matrix delivery channels for receiving matrices from multiple magazines, escapement means for the magazines, auxiliary key rods carried by the auxiliary delivery channel and movable therewith to and from operative position, primary key rods movable to and from operative position relative to the escapement means of one of the magazines, and means for communicating movement to said auxiliary key rods from said primary key rods.

20. In a typographical machine, in combination, multiple magazines in different operative planes, a matrix delivery channel, key rods connecting with the magazines in the lower operative plane, other key rods connecting with another magazine in an upper plane, and means whereby the said bottom of matrix delivery channel may serve to communicate movement from the upper to the lower key rods.

21. A typographical machine having a plurality of matrix magazines arranged for connection at the discharging and receiving ends, respectively, with primary and auxiliary matrix delivery and magazine entrance means, common assembling and distributing means for the magazines, said primary and auxiliary entrance means being operatively associated with said distributing means, and said auxiliary delivery and entrance means being connected for effecting

the simultaneous movement thereof for changing their relation to the magazines.

22. A typographical machine having a plurality of matrix magazines connected at opposite ends with primary and auxiliary delivery and entrance means, the primary and auxiliary entrance elements being operatively connected, the auxiliary elements being connected for simultaneous operation, and said primary and auxiliary elements being connected, respectively, with separate magazines.

23. A typographical machine having a plurality of matrix magazines and primary and auxiliary delivery and entrance means connected with two of the magazines, the primary elements being stationary and connected with one of the magazines, and the auxiliary elements being movably connected with the other of said magazines and arranged for simultaneous operation.

24. A typographical machine having a plurality of matrix magazines connected at opposite ends with primary and auxiliary delivery and entrance means, the primary and auxiliary entrance elements being interconnected, the primary and auxiliary delivery elements being also inter-connected, said auxiliary delivery and entrance elements being arranged for simultaneous operation, and the primary and auxiliary elements of said delivery and entrance means respectively being connected with separate magazines.

35. 25. A typographical machine having a plurality of matrix magazines and primary and auxiliary delivery and entrance means connected with two of said magazines, the magazines being selectively movable into and out of operative relation with said delivery and entrance means, the primary elements of said delivery and entrance means being stationary, and the auxiliary elements thereof being movable simultaneously for changing their relation to the magazine.

26. A typographical machine having a plurality of matrix magazines, primary and auxiliary delivery and entrance means connected with and for rendering two of said magazines operative, and means for rendering the magazines selectively operative relative to said delivery and entrance means, the primary elements of each of said means being connected with one, and the auxiliary elements thereof with the other of the operative magazines and capable of movement simultaneously into and out of operative relation.

27. A typographical machine having a plurality of matrix magazines selectively movable to and from operative position, primary matrix delivery means arranged for connection with one of the magazines, auxiliary delivery means including key rods

for releasing the matrices arranged for connection with another of the magazines, matrix distributing means therefor, means for preventing the operation of said distributing means when the magazines are moved, and means for controlling the interruption of said distributing means by the movement of the key rods of said auxiliary delivery means into operative position relative to one of said magazines.

28. A typographical machine having a plurality of matrix magazines, distributing means therefor, primary matrix delivery means, and relatively movable auxiliary delivery means for rendering two of the magazines simultaneously operative including key rods for releasing the matrices, means for interrupting the movement of said distributing means during the movement of the magazines and for permitting the continuous operation thereof when the key rods of said auxiliary delivery means are moved to operative position relative to one of the magazines.

29. In a typographical machine, in combination, a plurality of removable magazines housed in a frame, entrance and delivery channels therefor, means for adjusting the magazines relative to said entrance and delivery channels, means for removing one of said magazines without disturbing the operative relation of the other magazines, and relatively adjustable means attached to the side of the machine for receiving the magazines when they are removed from their housing.

30. In a typographical machine, in combination, a plurality of matrix magazines, entrance and delivery channels therefor, means for adjusting the magazines relative to said channels, one element of said adjusting means comprising a transverse shaft having an operating member at one terminus thereof convenient to the operator, and a series of key rods, certain of said rods being deflected so as to permit the extension of said shaft through the series of key rods, as described.

31. In a typographical machine, the combination of a plurality of matrix magazines selectively movable about a pivot, a normally stationary entrance channel member mounted on said pivot and movable when locked to said magazines by the interposition of an improperly distributed matrix, and means whereby the initial movement of said entrance channel may prevent further movement of the magazines until said improperly distributed matrix has been removed.

32. In a typographical machine, the combination of multiple matrix magazines selectively movable therein, a primary entrance channel movable therewith, a rela-

tively stationary entrance channel intermediate of the primary entrance channel and the magazines, means for permitting the continued distribution of the matrices to their proper magazines subsequent to the movement of said magazine to operative position, distributing means for advancing the matrices to the entrance means, and means for automatically interrupting the movement of said distributing means during

the movement of the magazines and said primary entrance channels relative to the intermediate channels.

Signed at Los Angeles, California, 7th day of December, 1915.

GEORGE E. MARLATT.
